ATTY.

UNITED STATES PATENT OFFICE.

CHARLES C. BARBER, OF FREEPORT, NEW YORK, ASSIGNOR TO WESTERN ELECTRIC COMPANY, OF NEW YORK, N. Y., A CORPORATION OF NEW YORK.

CENTRIFUGAL GOVERNOR.

Application filed June 27, 1921. Serial No. 480,681.

This invention relates to centrifugal controlling devices and is directed more particularly to a centrifugal switch operating mechanism.

5 The specific embodiment of the invention described hereinafter is an alarm circuit operating mechanism, the function of which is to indicate abnormally high and low speeds of a rotating shaft. The mechanism 10 comprises a centrifugally responsive device or governor, and a set of contact springs operable by said governor to close one or the other of two alarm circuits whenever the speed of the shaft goes above or 15 below normal.

The object in view is the provision of simple and effective means for regulating the action of a centrifugal governor over a wide range of speeds, and in accordance 20 with this object the characterizing feature of the invention consists in mounting the retractile springs of the governor on pliable arms which may be bent so as to shift the position of the springs with respect to the 25 pivotal points of the lever arms, thereby varying the moment of resistance to centrifugal force. Not only does this provide a very simple, effective and economical construction, but it insures permanency of regulation as there are no parts which can get 30 out of adjustment of their own accord.

Reference will now be had to the drawing for a more complete description of the invention.

35 Figure 1 is an elevational view of the alarm mechanism with the casing shown in cross-section;

Figure 2 is a cross-sectional view along the line 2-2 of Figure 1;

40 And Figure 3 is a cross-sectional view along the line 3-3 of Figure 2.

To the rotatable spindle 1 there is securely fixed a collar 2. The lever arms 3 are pivotally secured to the collar 2 by means of 45 pins 4. Lever arms 5 are each pivotally secured to one of the lever arms 3 by means of pin 6, and are also pivotally secured to the bushing 7 by pins 8. The bushing 7 is mounted on the end of spindle 1 and is free to move longitudinally thereon.

To each lever arm 3 there is riveted a pair of angle brackets 9, and the springs 10 are attached to the laterally extending arms of these brackets. The springs 10 operate to

55 restrain the toggles comprising lever arms 3 and 5 against centrifugal force, and when the spindle 1 is stationary, the toggles are held retracted by said springs, as shown in full lines in Figure 1. When the spindle is rotated, the toggles move outwardly against 60 the tension of springs 10 in response to centrifugal force, as indicated by the dotted outline in Figure 1.

Bushing 7 is moved longitudinally on the spindle in response to the lateral movement 65 of the toggle as will be evident, and accordingly any increase in the speed of spindle 1 will cause the movement of bushing 7 to the right, as viewed in Figure 1. Likewise, any decrease in the speed of the spindle will 70 effect the movement of bushing 7 toward the left.

The operating contact spring 11 is disposed between contact springs 12 and 13. Spring 11 is provided with an insulating 75 stub 14 which is pressed against bushing 7, and spring 11 accordingly follows the longitudinal movement of said bushing. When the spindle is stationary, or operating below 80 normal speed, contact springs 11 and 12 are engaged as shown in Figure 1, and a suitable alarm circuit for indicating abnormally low speed is closed by the latter spring.

With the spindle at normal speed, spring 85 11 is held out of engagement with the contacts of both springs 12 and 13, and when the speed exceeds normal, the contact of spring 11 is brought into engagement with the contact of spring 13. A second alarm circuit for indicating abnormally high speed 90 is closed through springs 11 and 13.

Angle brackets 9 are made preferably of pliable metal, such as brass, and the laterally extending arms thereof to which retractile 95 springs 10 are attached, are adapted to be bent to permit shifting the positions of springs 10 with respect to the positions of pivot pins 4. It will be seen that if the angle brackets are bent until the retractile springs are as near as possible to the center 100 of pins 4, the moment of resistance to centrifugal force will be reduced to a minimum, and if the brackets are bent so as to move the springs away from the center of pins 4, the opposite result will obtain.

The spindle 1 is intended to run at a constant speed, and the governor is adjusted to maintain the contacts between springs 11, 12

and 13 open so long as the speed does not vary more than a small amount either way from normal.

The governor may be adjusted to maintain the contacts open at any speed over a very wide range by bending the angle brackets as previously described.

What is claimed is:

1. In a centrifugal governor, a pair of 10 rotatably mounted toggles, a pair of springs, two pairs of separately adjustable lugs carried by said toggles and normally projecting at right angles to the plane of said toggles, each of said springs connecting the free 15 ends of a pair of said lugs, said lugs being

adjustable toward and away from the pivotal points of the toggle.

2. In a centrifugal governor, the combination of a toggle joint lever system mounted on a rotatable shaft, a pair of springs, a 20 pair of pliable lugs secured on opposite faces of each toggle, one lug of each pair cooperating with the corresponding lug of the other pair to anchor at their free ends one of said springs, the position of said 25 springs being adjustable by said lugs in a direction parallel to the axis of the shaft.

In witness whereof, I hereunto subscribe my name this 23rd day of June A. D., 1921.

CHARLES C. BARBER.
